Primary Examiner — David Muller(74) *Attorney, Agent, or Firm* — Stetina Brunda Garred & Brucker; Lowell Anderson(57) **CLAIM**

The ornamental design for an air filter with four elliptically-shaped filter cones, as shown and described.

DESCRIPTION

FIG. 1 is a perspective top view of an air filter with four elliptically-shaped filter cones, according to the invention.

FIG. 2 is a side view of the present invention.

FIG. 3 is a top view of the present invention.

FIG. 4 is a bottom view of the present invention; and,

FIG. 5 is a perspective bottom view of the present invention.
